UNITED STATES PATENT OFFICE.

WILLY BORRMANN, OF LEIPZIG-LEUTZSCH, GERMANY.

HAIR CLIPPER.

Application filed December 7, 1926, Serial No. 153,111, and in Germany May 4, 1926.

This invention relates to a hair clipper comprising an adjustable comb for varying the cutting height during the cutting. The hair clipper improved according to the invention presents the advantage over hair clippers of known type that the adjusting comb is shiftably guided in two directions the one at an acute angle to the other so that the comb may be adjusted during the hair clipping within the widest limits in any desired distance from the plane in which the clipping knives are situated, or to move the same along the knives away from the cutting edges of the same of such a distance that it becomes ineffective and the hair clipper can be used for making, during the hair clipping, cuts from the minimum length to the maximum length. In this manner cuts of any desired length can be made by means of this hair clipper without the necessity of exchanging elements or of carrying out complicated adjusting work.

According to the invention the adjusting comb is movably held by a slide which itself is guided on the machine frame near the cutting knives by means of a pull spring and connected at the other end to a hand lever in such a manner that the adjusting can be effected by according oscillation of the hand lever.

At the first phase of movement of the hand lever the comb which stands at a greater distance from the knife plane is moved towards the knives to be then shifted along the stationary knife so that it moves back completely and becomes ineffective. The guiding of the hair clipper and the adjusting of the comb can be carried out with one hand accurately as is the case with hair clippers without an adjusting comb.

An embodiment of the invention is shown, by way of example, in the accompanying drawings in which:—

Fig. 1 shows in side elevation, partly in longitudinal section, the improved hair clipper, the comb being adjusted to a great distance from the cutting point.

Fig. 2 is a view similar to Fig. 1, the comb being in a position close to the cutting point.

The hair clipper, consisting of a handle *a* a stationary knife *b* and a movable knife *d*, has a comb *g* in front of the stationary knife *b* which comb is held by a slide *h* and preferably constructed as a double comb in such a manner that a second comb *g'* is hingedly

connected to the points of the stationary comb *g* which is rigidly fixed on the slide. A blade spring *f* serves to press towards the stationary knife *b* the lower end of the comb *g'*, which is oscillatably mounted on the axle *i*. By the second comb *g'* the hair are well guided, this being of great importance for the proper execution of the cutting work. The slide *h* is pressed by the action of springs *k*, arranged near the cutting knives, from below against the handle *a*. The rear end of the slide *h* is hingedly connected to a pull rod *m* which passes through the rear transverse wall *a'* of the handle or casing *a* and which is at its other end pivotably connected to a hand lever *p* which is oscillatably mounted on an axle *n*. By means of this hand lever *p* and of the pull rod *m* the distance of the comb *g* from the cutting knives *b*, *d* may be altered at will during the clipping, it being merely necessary for this purpose to make the lever *p* oscillate towards the casing *a* in opposition to the pressure of a spring *s* or to release the hand lever *p* sufficiently so that the spring *s* can make it oscillate in opposite direction.

In order to adjust the machine for predetermined cutting lengths the pull rod *m* has several holes *o* and the transverse wall *a'* has a bore *r*, so that, by means of a pin to be inserted through one of the holes *o* into the bore *r*, the pull rod *m* and the hand lever *p* and through the same the comb *g* can be secured in any position.

In order to determine the minimum length of the cut, a second row of holes *t*, perpendicular to the direction of the row of holes *o*, may be arranged in the pull rod *m*. A pin inserted into one of said holes *t* serves as abutment to limit, by striking against the inner surface of the transverse wall *a'*, the longitudinal displacement of the slide *h*, whereby exciting of the desired minimum distance of the comb *g* from the knives *d*, *e* is determined.

In the form of construction shown it is supposed, that the slide *h* be situated outside the casing. The slide may, however, be arranged so that it is guided inside the casing *a* and projects from the casing merely in the area of the cutting point.

I claim:—

A hair clipper, comprising in combination a handle, a stationary knife and a movable knife standing at an acute angle to said

handle, a comb in front of said knives, a slide shiftably mounted on the lower surface of said handle its front portion being bent at the same acute angle at which said knives stand to said handle, a link connecting said comb to said slide, a spiral spring for pulling said slide from below towards said handle, a pull rod hingedly and adjustably mounted on the rear end of said slide, a

hand lever oscillatably mounted on said handle close to said knives and pivotably connected approximately at the middle, to said pull rod, and a blade spring acting upon the inner end of said hand lever and pressing the same away from said handle.

In testimony whereof I affix my signature.

WILLY BORRMANN.
